[57] CLAIM

The ornamental design for an electronic dip dispenser substantially as shown and described.

DESCRIPTION

FIG. 1 is a perspective view of an electronic dip dispenser embodying my new design;

FIG. 2 is a front elevational view of the electronic dip dispenser of FIG. 1;

FIG. 3 is a left side elevational view of the electronic dip dispenser of FIG. 1, the right side being a mirror image thereof;

FIG. 4 is a top plan view;

FIG. 5 is a rear elevational view; and

FIG. 6 is a bottom plan view thereof.

FIG. 1

FIG. 2

FIG. 3

FIG. 4

FIG. 5

FIG. 6
